US00D423742S

United States Patent [19]

Kingry et al.

[11] **Patent Number:** Des. 423,742[45] **Date of Patent:** ** *Apr. 25, 2000[54] **DUSTING MOP**

[75] Inventors: **Gary William Kingry**, Cincinnati; **Wilbur Cecil Strickland**, Loveland; **Michael Earl Hardy**, Cincinnati, all of Ohio; **Philip Ebwin Hague**, Chicago, Ill.

[73] Assignee: **The Procter & Gamble Company**, Cincinnati, Ohio

[*] Notice: This patent is subject to a terminal disclaimer.

[**] Term: **14 Years**

[21] Appl. No.: **29/094,261**

[22] Filed: **Sep. 29, 1998**

Primary Examiner—Alan P. Douglas*Assistant Examiner*—Lavone D. Tabor*Attorney, Agent, or Firm*—James C. Vago; Elizabeth M. Koch[57] **CLAIM**

The ornamental design for a dusting mop, as shown and described.

DESCRIPTION

FIG. 1 is a perspective view of a dusting mop, embodying our new design; and

FIG. 2 is a side view thereof, the opposite side view being the same;

FIG. 3 is a front view thereof, the back view being the same;

FIG. 4 is a top plan view thereof;

FIG. 5 is a bottom plan view thereof; and,

FIG. 6 is top plan view of a second embodiment of the design that is shown in FIGS. 1-5 with the only difference residing in the configuration of the raised designs set in the semicircular recesses.
